CLAIM

The ornamental design for a gameboard piece, as shown and described.

DESCRIPTION

FIG. 1 is an isometric top view of a gameboard piece showing the new design;

FIG. 2 is an isometric bottom view thereof;

FIG. 3 is a top view thereof;

FIG. 4 is a bottom view thereof;

FIG. 5 is a rear view thereof;

FIG. 6 is a front view thereof; and,

FIG. 7 is a right side view thereof with the left side view being identical.

All unshaded surfaces between solid and broken lines form no part of the claimed design. The broken lines in the drawings illustrate portions of the gameboard piece that form no part of the claimed design.

1 Claim, 7 Drawing Sheets
